[57] **CLAIM**

An ornamental design for combined top and bottom cartridge shells, as shown and described.

DESCRIPTION

FIG. 1 is a bottom exploded perspective view of combined top and bottom cartridge shells;

FIG. 2 is a top plan view of the top cartridge shell of FIG. 1 as viewed from the top;

FIG. 3 is a bottom plan view of the bottom cartridge shell of FIG. 1 as viewed from the bottom;

FIG. 4 is a bottom plan view of the top cartridge shell of FIG. 1 as viewed from the bottom;

FIG. 5 is a top plan view of the bottom cartridge shell of FIG. 1 as viewed from the top;
FIG. 6 is a front elevation of the top cartridge shell of FIG. 1;
FIG. 7 is a rear elevation of the top cartridge shell of FIG. 1;
FIG. 8 is a side elevation view of the top cartridge shell of FIG. 1;
FIG. 9 is another side elevation of the top cartridge shell of FIG. 1;
FIG. 10 is a front elevation of the bottom cartridge shell of FIG. 1;

FIG. 11 is a rear elevation of the bottom cartridge shell of FIG. 1;
FIG. 12 is a side elevation view of the bottom cartridge shell of FIG. 1; and,
FIG. 13 is another side elevation of the bottom cartridge shell of FIG. 1.
The broken line drawing in FIG. 1 is for illustrative purposes only and forms no part of the claimed design. The top and bottom shells are shown separately in FIGS. 2-13 for ease and clarity of illustration.
